UNITED STATES PATENT OFFICE.

LESTER KYLE ALDRICH, OF SIDNEY, OHIO.

AUTOMATIC PAPER-ELEVATOR CONTROL FOR AUTOMATIC SHEET FEEDERS.

Application filed October 26, 1927. Serial No. 228,814.

The invention relates to an automatic paper elevator control for automatic sheet feeders such as is disclosed in Patent No. 1,546,184, granted to me July 14, 1925.

5 The object of the present invention is to improve the construction of automatic paper elevator controls for automatic sheet feeders and to provide a simple, practical and efficient automatic paper elevator control of strong, 10 durable and comparatively inexpensive construction adapted to automatically control the mechanism for elevating the stack of paper for automatically lifting the stack and for maintaining the top of the pile at a predetermined level.

A further object of the invention is to give a greater range to the control mechanism and to provide one which can be assembled in units and produced at a minimum cost.

20 Another object of the invention is to provide an automatic paper elevator control which will be fool-proof and which cannot be gotten out of adjustment and in which repair parts may be installed by a novice.

25 Another object of the invention is to provide an automatic paper elevator control equipped with a feeler finger provided with a roll adapted when the feeder is running small sheets to be held firmly in engagement with the same to enable the feeder to throw a greater loop or undulation in the paper and give a better separation of the sheets and capable when the feeder is operating on large sheets to turn freely and allow a sheet which has 30 been dragged slightly forward to be restored to proper position by a hold-down and register mechanism shown and described in my co-pending application filed June 2, 1927, Serial No. 196,208.

40 Another object of the invention is to provide means for counter-balancing the feeler finger to enable the same to operate on the tail of envelopes without tipping the envelopes up at the front.

45 A further object of the invention is to provide an automatic paper elevator control in which the only adjustment required will be an adjustment of the feeler finger to arrange the same to suit the size of the sheets and the 50 character of the stock to be fed by an automatic feeder.

With these and other objects in view, the invention consists in the construction and novel combination and arrangement of parts herein-after fully described, illustrated in the accompanying drawings and pointed out in the

claims hereto appended, it being understood that various changes in the form, proportion and minor details of construction, within the scope of the claims, may be resorted to without departing from the spirit or sacrificing any of the advantages of the invention.

In the drawings:

Figure 1 is a plan view of an automatic paper elevator control constructed in accordance with this invention and shown applied to a feeder.

Fig. 2 is a transverse sectional view illustrating the manner of mounting the vertically movable elevator board or table.

Fig. 3 is an enlarged end elevation of the automatic paper elevator control.

Fig. 4 is a side elevation of the same.

Fig. 5 is an enlarged plan view of the automatic paper elevator control.

In the accompanying drawings the automatic paper elevator control is shown applied to the automatic feeder of the aforesaid patent, but it is adapted to be applied to various other automatic feeders as will be readily understood. The feeder of the aforesaid patent comprises in its construction a frame 1 substantially rectangular in plan view and composed of spaced sides connected by suitable cross bars. A vertically movable 85 table or elevator board 2 is provided for supporting a stack of sheets 3 that are to be fed by the automatic feeder. The table 13 is automatically moved upwardly for advancing the stack 3 by elevating mechanism comprising a tubular shaft consisting of a sleeve 4 extending across the frame of the machine and arranged between the sides thereof and provided at its ends with interiorly arranged anti-friction bearings 5 which are mounted on a transverse supporting rod 6. The transverse supporting and connecting rod 6 extends entirely across the frame and is firmly and detachably secured in aligned transverse openings 7 by means of clamping screws 8 mounted in suitable threaded openings 9 in the top portions of the sides of the frame of the machine. The threaded openings 9 extend downwardly from the upper edges of the sides of the machine to the transverse openings 7 and the clamping screws 8 which are provided at their upper ends with suitable heads for engagement by a wrench or other tool firmly clamp the terminal portions of the cross rod 5. The anti-friction bearings 5 which

95 are of any desired construction are 100 105 110

mounted in counter-bores or enlargements 10 of the end portions of the opening through the sleeve. The counter-bores or enlargements 10 of the bore or opening through the sleeve forms shoulders against which the anti-friction bearings abut. The sleeve 4 is supported in spaced relation with the rigid cross rod 6 by the roll or other anti-friction bearings which reduce the friction to a minimum and at the same time simplify the construction by combining in one structure the connecting rod and shaft. This affords greater freedom in placing the stack upon the elevator board or table.

15 The elevator board or table 2 is supported by sprocket chains 11 arranged on sprocket wheels 12 mounted on the end portions of the sleeve 4 and secured to the same by clamping screws 13 or other suitable means. The sprocket chains are secured at one end to the vertically movable elevator board or table and their other ends are free and are provided with a counter-weight or balance as explained in the aforesaid patent. The sleeve 4 also has mounted on it a worm wheel 14 located at one end of the sleeve adjacent one side of the frame and secured to the sleeve by a clamping screw 15 or other suitable means. The clamping screw 15 detachably secures the worm to the sleeve and it will be apparent that when the worm becomes worn and requires repair or replacement the rod 6 may be readily withdrawn from the frame to afford access to the worm wheel without disturbing the adjustment of the sprocket wheels. This will enable the worm wheel to be readily replaced by an inexperienced person and the sleeve may be readily replaced in the frame and the connecting rod 6 returned to its proper position. The worm wheel meshes with a worm 16 of a shaft 17 journaled in suitable bearings 18 of the adjacent side of the frame and designed to be equipped at one end with a hand wheel as explained in the aforesaid patent. The worm drives the tubular shaft or sleeve 4 and rotates the sprocket wheels for elevating the vertically movable elevator board or table through the connecting sprocket chains.

20 The shaft 17 extends longitudinally of the machine above the adjacent side of the frame and the means for automatically rotating the shaft 17 for elevating the vertically movable table 2 comprises a ratchet wheel 19 fixed to the shaft 17 by means of a clamping screw 20 or other suitable means and it is engaged by an actuating pawl 21 pivoted at 22 to an oscillating member 23 preferably consisting of a casting and disposed transversely of the machine and provided at its outer end with an arm 24 which is connected by a link 25 with the mechanism of the feeder as explained in the aforesaid patent. The upper end of the link 25 is provided with a slot 26 in which 25 operates a headed pivot 27 mounted on the arm 24. The link, as explained in the aforesaid patent, is continuously reciprocated and on its downward movement is adapted to actuate the arm 24 and through the pawl 21 to partially rotate the ratchet wheel and the shaft 17 on which the ratchet wheel is mounted. The actuating pawl 21 is moved backwardly in a counter-clockwise direction by a weight 28 formed integral with the oscillatory member as explained in the aforesaid patent. The weight 28 is adapted to lift the arm 24 as the link 25 moves upwardly and the link in its downward movement actuates the arm 24 to elevate the vertically movable table 2. The oscillatory member 23 is provided with a lug 29 forming a shoulder which is adapted to rest upon a control finger 30 which when the stack is elevated to the predetermined level is moved by the means hereinafter described to a position beneath the lug whereby the weighted inner portion of the oscillatory member will be supported in an elevated position to maintain the outer arm 24 in its lower position. The slot 26 will permit the link 25 to reciprocate without actuating the arm 24 so that while the lug and the weighted inner portion of the oscillatory member is supported in an elevated position by the control finger the elevating mechanism will remain stationary until the sheets from the top of the stack to be fed, sufficiently to cause a feeler finger 31 to move downwardly and actuate the control finger and swing the latter from beneath the lug 29 to permit the weight 28 to partially rotate the oscillatory member and elevate the outer arm 24 so that the link 25 in its reciprocation will move the arm 24 downwardly and rotate the ratchet wheel with a step by step movement until the stack is again elevated to the predetermined level and causes the feeler finger 31 to return the control finger to its supporting position. The oscillatory member, as explained in the aforesaid patent, is loose on the shaft 17 and it is maintained in proper position with relation to the ratchet wheel 19 by means of a suitable collar 32 secured by a set screw 33 or other suitable means to the shaft 17. The control finger which is approximately straight and vertical is secured at its lower portion by screws 33 or other suitable fastening devices to an upwardly extending arm 35 of a lever 36 pivotally mounted on a stud 37 and having an angularly related approximately horizontally disposed arm 38 which is rigid with the finger. The stud 37 is mounted on a bracket 39 consisting of a plate suitably secured to the frame of the machine and provided at its upper portion with a stop lug 40 arranged in the path of the control finger for limiting the movement thereof when the vertically movable table 2 is empty and the feeler finger 31 is not supported by a stack of sheets. The upper end 41 of the control finger is beveled 130

to reduce to the desired extent the area of the supporting surface provided for engagement with the lug 29 of the oscillatory member so that a comparatively slight movement of the 5 feeler finger will operate the control finger. The arm 38 is provided with an open slot or bifurcation 42 which receives the terminal portion 43 of an arm 44 of a rock shaft 45 disposed longitudinally of the feeder and 10 provided at its ends with cone bearing recesses 46 and mounted on cone journals 47. The cone journals which are longitudinally aligned are adjustably and detachably mounted in openings 48 of spaced supporting arms 15 49. The supporting arms 49 which extend inwardly from the adjacent side of the frame are provided at their lower faces with threaded openings 50 for the reception of clamping screws 51 which detachably secure the cone 20 pins or journals in the openings 48 of the supporting arms. The supporting arms are preferably provided at their outer ends with reduce threaded portions 52 which pierce the sides of the frame and are secured to the 25 same by nuts 53. By this construction the device may be readily mounted as a unit on the frame of the feeder. The terminal portion of the arm 44 is rounded to work in the bifurcation or slot 42 of the arm of the lever 30 which carries the control finger and the said arm 44 is downwardly offset at 54 by angular bends to arrange it clear of the hold-down and register mechanism of the aforesaid application which is designed to be employed 35 on the larger type of feeders. When, however, the present invention is applied to feeders of the smaller type not employing the said register and hold-down mechanism the downwardly offset portion 54 may be omitted 40 and the bifurcated arm 38 may be arranged in the plane of the pivot stud 37. This will enable a straight arm to be employed instead of the angularly bent arm 44 and will simplify the construction in such small feeders. 45 The rock shaft consists of a flat bar oblong in cross section having its side faces arranged substantially vertical when in normal position and the arm 44 is secured by a screw 50 to the outer face of the bar or shaft 45. Any other suitable means may, of course, be employed for securing the arm 44 to the bar 45 which forms a guide for a slide 56 provided with a substantially oblong opening 57 to fit the bar 45 and it has a slot 58 at its outer 55 side adapted to clear the detached inner end of the arm 44. The opening 57 is enlarged at the inner portion to reduce the friction and the slide is provided with a thumb screw 59 mounted in a threaded opening 60 of the 60 slide and arranged to engage the shaft or bar 45 for securing the slide in its adjustment. The slide carries an arm 61 consisting of a rod mounted in a suitable opening 62 in the inner side of the slide and having mounted on 65 it the feeler finger 31. The feeler finger 31 is provided with a head or enlargement 63 having an opening 64 through which the arm 61 passes and the feeler finger is adjustably mounted on the arm 61 by means of a clamping screw 65. Through the longitudinal adjustment of the slide on the bar or shaft 45 and the transverse adjustment of the feeler finger 31 on the arm 61 of the slide, the feeler finger may be positioned at any desired point or over the vertically movable table to arrange it to suit the size of the sheets to be fed. The feeler finger is provided at its outer or front end with a roll 66 mounted on a screw 67 or other suitable fastening device which is threaded into the feeler finger at 68 and is 70 provided with a lock nut 69 for securing the screw in its adjustment. The screw which forms a pivot for the roll is adapted to permit the roll to rotate freely when the feeder is operating on large sheets and it is adapted 75 to firmly clamp the roll against the finger to provide a rigid engagement between the finger and the sheets when small sheets are being fed. This will enable the feeder to throw a greater loop or undulation in the 80 paper and give a better separation of the sheets when running smaller sizes of paper. When the feeder is operated on large sheets the screw is adjusted to permit the roll to turn freely so that the said hold-down and register mechanism may return to proper position a sheet which has been dragged slightly forward by the feeder in feeding the preceding sheet. The shaft or bar 45 is provided at 85 the opposite end to that at which the arm 100 44 is located with a counter-balancing arm 70 having a reduced end 71 threaded into the shaft or bar 45, but the arm 70 may be constructed in any other desired manner. The arm 70 is equipped with an adjustable 105 counter-balancing weight 72 secured in its adjustment by a clamping screw 73 and adapted to be positioned on the arm 70 so as to counter-balance or nearly counter-balance the feeler finger and thereby control 110 the pressure of the finger against the sheets or other articles, such as envelopes, being fed by the machine. This will enable the feeler finger to rest upon a stack of envelopes at one end without liability of tipping the other 115 end upward and interfering with the proper feeding of the envelopes. By means of the counter-balancing weight the pressure of the feeler finger may be properly adjusted to suit the size of the sheets and the character of 120 the stock. The automatic elevating mechanism is equipped with a second ratchet wheel 74 mounted on the shaft 17 and rigidly secured to the same by a clamping screw 75 or other 125 suitable means and engaged by a check pawl 76. The check pawl 76 is mounted on suitable pivots 77 carried by a bracket 78 and preferably secured in an opening thereof by means of a set screw 79. The check pawl 130

is adapted to hold the shaft 17 against retrograde rotation while the pawl is moving in a counter-clockwise direction. The second pawl and ratchet will effectually prevent 5 back-lash of the elevating mechanism.

What is claimed is:—

1. An automatic paper elevator control including a frame, a vertically movable table adapted to support a pile of sheets, a cross 10 rod extending across the frame and detachably secured to the same, a tubular shaft consisting of a sleeve mounted on the cross rod and supported in spaced relation with the same, sprocket wheels carried by the tubular 15 shaft the said sleeve and sprocket wheels being adapted to be removed as a unit when the cross rod is detached, sprocket chains arranged on the sprocket wheels and connected with the vertically movable table, gearing 20 connected with the tubular shaft for rotating the same to raise and lower the table, means for actuating the gearing step by step, a feeler adapted to rest upon the stack of sheets supported by the said table, and means actuated by the feeler for controlling the operation 25 of the gearing.

2. An automatic paper elevator control including a frame having spaced sides, a cross rod extending across the frame and detachably secured at its ends to the sides thereof, a tubular shaft consisting of a sleeve mounted 30 on the cross rod and provided with interior bearings supporting the shaft in spaced relation with the said rod, sprocket wheels 35 mounted on the tubular shaft, the said sleeve and sprocket wheels being adapted to be removed as a unit when the cross rod is detached, sprocket chains arranged on the sprocket wheels and connected with the vertically 40 movable table, a worm wheel also mounted on the tubular shaft, a longitudinally disposed shaft having a worm meshing with the worm wheel, means for actuating the longitudinal shaft step by step, a feeler 45 adapted to rest upon the top of the stack of sheets supported by said table, and means actuated by the feeler for controlling the operation of the mechanism for rotating the longitudinal shaft.

3. An automatic paper elevator control including a frame having spaced sides, a cross rod connecting the sides and detachably secured to the same, a tubular shaft extending across the frame and provided with interior 55 bearings supporting the tubular shaft in spaced relation with the said rod, the said tubular shaft and bearings being adapted to be removed as a unit when the cross rod is detached, vertically movable table adapted 60 to support a stack of sheets, means whereby the rotation of the shaft raises or lowers said table, a worm wheel mounted on the tubular shaft, a longitudinal shaft having a worm meshing with the worm wheel, mechanism for 65 rotating the longitudinal shaft step by step,

a feeler adapted to rest upon the stack of sheets supported by the table and means actuated by the feeler for controlling the operation of the mechanism for rotating the longitudinal shaft.

4. An automatic paper elevator control including a frame having spaced sides, a vertically movable table adapted to support a stack of sheets, a cross rod connecting the sides of the frame and detachably secured to the same, a tubular shaft consisting of a sleeve arranged on the cross rod and having its opening enlarged at the ends, anti-friction bearings mounted in the enlarged ends of the opening of the sleeve and supporting the same in space relation with the cross rod, sprocket wheels mounted on the tubular shaft, the tubular shaft, the sprocket wheels and the bearings being adapted to be removed as a unit when the cross rod is detached, sprocket 80 chains connected with the vertically movable table and arranged on the sprocket wheels, a worm wheel mounted on the shaft at one end thereof, a longitudinal shaft having a worm meshing with the worm wheel, mechanism for 85 rotating the longitudinal shaft step by step to elevate the table, a feeler adapted to rest upon the stack of sheets supported by the table, and means actuated by the feeler for controlling the operation of the mechanism 90 for rotating the longitudinal shaft.

5. An automatic paper elevator control including a vertically adjustable table adapted to support a pile of sheets, means for raising the table step by step, including a pawl, a ratchet and a weighted oscillatory member adapted to move the pawl in one direction, a substantially vertical control finger movable to and from a position beneath the oscillatory member for supporting the same out of operation, said control finger having an angularly related arm, a longitudinally disposed rock shaft provided with an arm connected to and directly actuating the arm of the control finger and a feeler carried by the rock shaft 100 and adapted to rest upon the stack of sheets supported by said table and adjustable along the rock shaft to engage sheets of different sizes.

6. An automatic paper elevator control including a vertically adjustable table adapted to support a pile of sheets, means for raising the table step by step, including a pawl, a ratchet and a weighted oscillatory member adapted to move the pawl in one direction, a substantially vertical control finger pivotally mounted at the lower end and provided with an angularly related arm, said finger being movable to and from a position beneath the oscillatory member for supporting the latter out of operation, a longitudinally disposed rock shaft having an arm directly connected to the arm of the control finger for actuating the latter, and a feeler carried by the rock shaft and adapted to rest upon the stack of 115 120 125 130

sheet supported by the table and adjustable along the rock shaft to engage sheets of different sizes.

7. An automatic paper elevator control including a vertically adjustable table adapted to support a pile of sheets, means for raising the table step by step, including a pawl, a ratchet and a weighted oscillatory member adapted to move the pawl in one direction, a bracket mounted on the frame and having a stud, an angle lever pivotally mounted on the stud, an approximately vertical control finger carried by one arm of the said lever and movable to and from a position beneath the oscillatory member for supporting the latter in inoperative position, a longitudinally disposed rock shaft having an arm directly connected to the other arm of the said lever, and a feeler carried by the rock shaft and adapted to rest upon the stack of sheets supported by the said table and adjustable along the rock shaft to engage sheets of different sizes.

8. An automatic paper elevator control including a vertically adjustable table adapted to support a stack of sheets, means for raising the table step by step, including a pawl, a ratchet and a weighted oscillatory member adapted to move the pawl in one direction, an angle lever arranged to swing longitudinally of the table and having an approximately vertical control finger movable to and from a position beneath the oscillatory member for supporting the latter in an inoperative position, a rock shaft extending longitudinally of the table and provided with an arm connected directly to the angle lever for actuating the control finger, and a feeler carried by the rock shaft and adapted to rest upon the stack of sheets supported by the table and adjustable along the rock shaft to engage sheets of different sizes.

9. An automatic paper elevator control including a vertically adjustable table adapted to support a stack of sheets, means for raising the table step by step, including a pawl, a ratchet and a weighted oscillatory member adapted to move the pawl in one direction, an angle lever pivoted at its angle and having at one arm a substantially vertical control finger movable to and from a position beneath the oscillatory member for supporting the latter in an inoperative position, the other arm of the lever being provided with a slot, a longitudinal rock shaft provided with an arm downwardly offset and provided with a terminal portion operating in the slot of the angle lever, and a feeler carried by the rock shaft and arranged to rest upon the stack of sheets supported by the table.

10. An automatic paper elevator control including a vertically adjustable table adapted to support a stack of sheets, means for raising the table step by step, including a pawl, a ratchet and a weighted oscillatory member adapted to move the pawl in one direction,

control mechanism comprising spaced supports provided with means for securing them to a feeder, a bracket located between the supports, a lever pivotally mounted on the bracket and having a substantially vertical control finger arranged to swing longitudinally of the table and movable to and from a position beneath the oscillatory member to support the latter in an inoperative position, a longitudinal rock shaft mounted between the spaced supports and provided with an arm extending to and directly connected with the said lever for actuating the control finger, and a feeler carried by the rock shaft and arranged to rest upon the stack of sheets supported by the table.

11. An automatic paper elevator control including a vertically adjustable table adapted to support a stack of sheets, means for raising the table step by step, including a pawl, a ratchet and a weighted oscillatory member adapted to move the pawl in one direction, control mechanism comprising a lever arranged to swing longitudinally of the table and having a control finger movable to and from a position for supporting the oscillatory member and adapted to support the latter in an inoperative position, a longitudinal rock shaft, an arm extending from the rock shaft and directly connected to the said lever for actuating the control finger, a slide mounted on the bar and provided with an opening to permit it to clear the said arm, and a feeler carried by the slide and adapted to rest upon the stack of sheets and supported by the said table.

12. An automatic paper elevator control including a vertically adjustable table adapted to support a stack of sheets, means for raising the table step by step, including a pawl, a ratchet and a weighted oscillatory member adapted to move the pawl in one direction, control mechanism comprising a lever arranged to swing longitudinally of the table and having a control finger movable to and from a position for supporting the oscillatory member and adapted to support the latter in an inoperative position, a longitudinal rock shaft consisting of a flat bar, an arm extending from one of the side faces of the said bar and directly connected to the said lever, a slide mounted on the rock shaft and adjustable to different positions on the same and having an opening to enable it to clear the said arm, an inwardly extending arm carried by the slide, and a feeler mounted on the said inwardly extending arm and adapted to rest upon the stack of sheets supported by the table.

13. An automatic paper elevator control including a vertically adjustable table adapted to support a stack of sheets, means for raising the table step by step, including a pawl, a ratchet and a weighted oscillatory member adapted to move the pawl in one direction,

control mechanism comprising a pivotally mounted control finger movable to and from a position for supporting the oscillatory member out of operation, a longitudinal rock shaft 5 having inwardly and outwardly extending arms, the outwardly extending arm being connected with and adapted to actuate the control finger, and a feeler finger carried by the inwardly extending arm and provided with 10 a roll adapted to rest upon the stack of sheets supported by the table, said feeler finger having means for locking the roll against rotation and for holding the paper against sliding movement when feeding small sheets and 15 for permitting sliding movement of the paper when feeding large sheets.

14. An automatic paper elevator control including a vertically adjustable table adapted to support a stack of sheets, means for raising the table step by step, including 20 a pawl, a ratchet and a weighted oscillatory member adapted to move the pawl in one direction, a control finger movable to and from a position for supporting the oscillatory member 25 out of operation, a rock shaft connected with the control finger for actuating the same, and a feeler carried by the rock shaft and provided with a roll arranged to rest upon the stack 30 of sheets supported by the table, said feeler having means for locking the roll against rotation for holding small sheets against sliding movement and for permitting a sliding movement of large sheets, and an arm carried by 35 the rock shaft and provided with an adjustable weight arranged to counter-balance the feeler for controlling the pressure of the same upon the sheets to be fed.

15. An automatic paper elevator control 40 including a vertically adjustable table adapted to support a stack of sheets, means for raising the table step by step, including a pawl, a ratchet and a weighted oscillatory member adapted to move the pawl in one direction, 45 a control finger movable to and from a position for supporting the oscillatory member out of operation, a rock shaft connected with the control finger for actuating the same, a feeler carried by the rock shaft and provided with a roll arranged to rest upon the stack 50 of sheets supported by the table, said feeler having means for locking the roll against rotation for holding small sheets against

sliding movement and for permitting a sliding movement of large sheets, and means for counter-balancing the feeler for controlling the pressure of the same upon the sheets to be fed. 50

16. An automatic paper elevator control including a vertically adjustable table adapted 55 to support a stack of sheets, means for raising the table step by step, including a pawl, a ratchet and a weighted oscillatory member adapted to move the pawl in one direction, a control finger movable to and from a position for supporting the oscillatory member 60 out of operation, a rock shaft connected with the control finger for actuating the same, a feeler carried by the rock shaft and provided with a roll arranged to rest upon the stack 65 of sheets supported by the table, said feeler having means for locking the roll against rotation for holding small sheets against sliding movement and for permitting a sliding movement of large sheets, and an arm carried by 70 the rock shaft and provided with an adjustable weight arranged to counter-balance the feeler for controlling the pressure of the same upon the sheets to be fed. 75

17. An automatic paper elevator control including a vertically adjustable table adapted 80 to support a stack of sheets, means for raising the table step by step, including a pawl, a ratchet and a weighted oscillatory member adapted to move the pawl in one direction, a control finger movable to and from a position for supporting the oscillatory member 85 out of operation, a rock shaft having inwardly and outwardly extending arms, the outwardly extending arm being connected with and adapted to actuate the control finger, a feeler carried by the inwardly extending arm and arranged to rest upon the pile of sheets supported by the table, and an arm extending 90 from the rock shaft and at one end thereof and provided with an adjustable weight arranged to counter-balance the feeler for controlling the pressure of the same against the sheets to be fed. 95

In testimony whereof I affix my signature.
LESTER KYLE ALDRICH.
